UNITED STATES PATENT OFFICE.

JULIUS OTTO VON STETTEN AND HARRY J. PRESSMAN, OF PHILADELPHIA, PENNSYLVANIA, ASSIGNORS TO PHILADELPHIA METAL DRYING FORM COMPANY, OF NEW CASTLE, DELAWARE, A CORPORATION OF DELAWARE.

GARMENT-DRYING APPARATUS.

1,308,381.

Specification of Letters Patent. Patented July 1, 1919.

Application filed November 17, 1917. Serial No. 202,564.

To all whom it may concern:

Be it known that we, JULIUS OTTO VON STETTEN and HARRY J. PRESSMAN, respectively a subject of the Emperor of Austria and a citizen of the United States, residing at Philadelphia, county of Philadelphia, and State of Pennsylvania, have invented a new and useful Improvement in Garment-Drying Apparatus, of which the following is a full, clear, and exact description, reference being had to the accompanying drawings, which form a part of this specification.

Our invention relates to apparatus for drying garments over forms, and has for its principal object the holding of the garment on the form in a taut unwrinkled state suitable for drying with the best results.

We will show and describe our invention in connection with the tubular forms of a hosiery drier, but it is equally adaptable to similar forms for drying other garments.

Our invention consists of clamping members which are normally held against the form, and which, when the garment is applied to the form, are spaced apart by the operator and then allowed to return in position against the garment for holding same as described. The construction is such that the operation of the clamps does not require the operator to use his hands, which may be fully employed in mounting the garment on the form and smoothing it in place.

Our invention is applicable to drying forms of the kind described in which the forms are mounted vertically as well as those in which the forms are given an inclination with regard to the level of the table.

Furthermore, our invention has adjustable features, whereby the same apparatus may be used with garments of different lengths upon the forms.

Other features of advantage will be apparent from the following description in connection with accompanying drawings, which illustrate an embodiment of our invention applied to forms for drying men's hose.

Figure 1 is an elevation, partly broken away, of a portion of the apparatus.

Fig. 2 is a partial sectional view looking at the end of Fig. 1.

Fig. 3 is a horizontal section on line 3—3 of Fig. 1.

Fig. 4 is a plan view of one end of the drying table on which my invention is to be applied.

Fig. 5 is a partial longitudinal section of same.

Fig. 6 is a complete end view of a modification.

The garment drier to which we have shown our invention applied is of the form disclosed in a patent application filed by us October 2, 1917, Serial No. 194423.

The apparatus is arranged on a table *i* having a longitudinal channel in its surface, below which rests the steam piping carrying the drying forms. The exhaust pipe *a*, of relatively large diameter and extending the length of the table, is slightly flattened intermediate of its ends, and the flattened portion carries at intervals tubular metallic forms *b* upon which the wet garments are drawn for drying. The end stands *v* are curved out in their upper part to receive the round ends of pipe *a*, which are secured in place by portions *y*, curved in a similar manner to fit the pipe.

Steam is admitted through a relatively small pipe *c* running centrally through pipe *a*, which it enters at either end by a stuffing box *d*. From this pipe *c* nozzles project upwardly into the hollow forms *b* for distributing the steam, as described in the application referred to.

When hose are drawn over the forms, without any holding device thereon, the open ends of the hose gather and wrinkle and are dried in that condition. With our invention, hose *x* is drawn down over form *b* and its end held against the form by clamping members *e*, preventing such rough and irregular conditions for drying. Clamping members *e* are bent to conform to the curvature of the form and are carried on swinging frames *f*, on either side of the form, mounted on the same aligned pivots *g*. Pivots *g* are centrally located with respect to form *b* so that frames *f* swing clamping members *e* similarly and symmetrically toward and away from the form.

The pivots are carried by supports *h* attached to table *i*. Frames *f* are formed of thin sheet metal and carry ears projecting back, away from the operator, for connecting respectively with links *j*, *k*, by which the clamping frames are operated. Links

- j, k, extend below the table and are pivoted to a disk *m* at such points that when the disk is turned the links move in opposite directions. Disk *m* is mounted on a bracket*
- 5 *n* depending from the under side of the table, and is actuated by a rod *o* which extends out beyond the edge of the table toward the operator. Rod *o* is supported, as by bracket *p*, and is normally held in
- 10 outer position as by spring *r*. This spring acts in the direction to hold clamps *e* against form *b*, and the opening of said clamps is accomplished by the operator pushing in rod *o* with his body. This will turn
- 15 the disk in clock-wise direction, Fig. 2, which will raise link *j* and lower link *k*. These links act upon the ears of respective clamping frames *f* to tilt the frames into positions shown in broken lines.
- 20 When the operator has the garment *x* drawn taut over the form, as required, he releases rod *o* which allows spring *r* to press it outwardly and return the parts to normal position, in which clamping members *e* grip
- 25 the end of the garment, as shown in Fig. 1, and hold same as desired through the drying operation.

In order to accommodate garments of different lengths, the clamping frames are made 30 adjustable in length as by means of the slot and screw connection *s*.

When the forms are inclined, as shown in Fig. 6, supports *h* are secured to the table so as to bring the line of pivots *g* central 35 with respect to the inclined forms.

Adjustment of links *j, k*, is allowed for by several holes in each for connecting to the ears of frames *f*. By this means, the pressure of the clamping members against the 40 form may be equalized.

The mechanism may be so arranged as to be operated by the foot instead of the body, as shown in Fig. 6. In this arrangement, disk *m* is operated by a rod *t* connecting 45 with a foot treadle *u*, which is held normally raised, as by spring *w*. Spring *w*, in this case, acts as did spring *r* to hold the clamping members against the form, and the operation of the foot treadle to open the clamp 50 as did rod *r* in the first described form.

Having now fully described our invention, what we claim and desire to protect by Letters Patent is:

1. In a garment drier, the combination 55 with a hollow form over which a tubular garment to be dried is adapted to be stretched, of a clamp adapted to confine the open end portion of the garment against the outer wall of the form, said clamp comprising a member consisting of a longitudinally extensible and contractible frame to enable it to be adjusted to adapt it to garments of different length.

2. In a garment drier, the combination 60 with a hollow form over which a tubular

garment to be dried is adapted to be stretched, of a clamp adapted to confine the open end portion of the garment against the outer wall of the form, said clamp comprising a plurality of members each of 70 which consists of a longitudinally extensible and contractible frame and a clamping plate carried thereby, and means to move said frames in unison toward and from the form.

3. In a garment drier, the combination 75 with a hollow form over which a tubular garment to be dried is adapted to be stretched, of a clamp adapted to confine the open end portion of the garment against the outer wall of the form, said clamp comprising two members each of which consists of a longitudinally extensible and contractible frame and a clamping plate carried thereby, said frames being pivotally mounted and located on opposite sides of the form, 80 and means to swing said frames in unison toward and from the form.

4. In a garment drier, the combination 85 with a hollow form over which a tubular garment to be dried is adapted to be stretched, of a clamp movable toward the form to confine the open end portion of the garment against the outer wall of the form and movable away from the form to release the garment, mechanism to so operate the 90 clamp including a tension device arranged to move the clamp into operative position and manually operable means to move said clamp, against the action of the tension device, to release the form.

5. In a garment drier, the combination 95 with a hollow form over which a tubular garment to be dried is adapted to be stretched, of a clamp adapted to confine the open end portion of the garment against the outer wall of the form, said clamp comprising two swinging frames and clamping plates carried thereby, a turnable disk, links connecting the disk and the frames, manually operable means to turn the disk into position to retract the frames from the form, and a tension device tending to turn the disk in the opposite direction until the clamping plates move into clamping position.

6. In a garment drier, the combination 105 with a hollow form over which a tubular garment to be dried is adapted to be stretched, of a clamp adapted to confine the open end portion of the garment against the outer wall of the form, said clamp comprising two members located on opposite sides of the form and pivoted on a common axis, connecting links whose upper ends are both located at one side of the form and which are attached to the respective clamping members whereby reverse movements concurrently imparted to the two connecting rods will effect a simultaneous opening or closing of the clamping members, a turnable disk to which the lower ends of the con- 110

120

125

130

necting rods are attached, manually operable means to turn the disk to impart a clamp-opening movement to the connecting rods, and a tension device tending to turn the disk and move the connecting rods in the opposite direction.

7. In a garment drier, the combination with a hollow form over which a tubular garment is adapted to be stretched, of a 13 clamp adapted to confine the open end portion of the garment against the outer wall of the form, a table, means to adjust the

form to change its angle of inclination, a frame supporting the clamp, and means on the table supporting the frame, whereby the 15 clamp may properly coöperate with the form in different adjusted positions of the latter by positioning said supporting means accordingly.

In testimony of which invention we have 20 hereunto set our hands, at Philadelphia, Pa., on this 16th day of November, 1917.

JULIUS OTTO VON STETTEN.
HARRY J. PRESSMAN.
